UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

MACHINE FOR CASTING PRINTING PLATES WITHOUT A RISER.

Application filed April 30, 1926. Serial No. 105,819.

This is in part a division of my application Serial No. 721,272 filed June, 20, 1924, now patent 1,673,857, issued June 19, 1928, but contains additional matter.

- 5 This invention relates to an apparatus for the casting of printing plates without a riser in a solid state attached to the plate when cast.
- 10 The principal objects of the invention are to provide means for eliminating entirely the presence of the riser on the plate when cast without sacrificing any of the advantages which an ordinary riser provides so as to do away with the use of the mechanism ordinarily employed for sawing off a solid riser and yet leave the edge of the plate in a smooth condition and of the desired contour; to provide a machine which will avoid the loss of time and the slowing down in the production of plates necessitated by the sawing off of the riser, and also to provide means for avoiding the necessity of waiting until the plate is chilled before the riser cutting operation can be started, and
- 15 at the same time to produce a plate of less length than the matrix in which it is cast, and of no greater length than a similar plate from which the riser has been severed while cold; to provide for the automatic and
- 20 repeated operation of the machine; to provide for quick and automatic separation of the plate from the core; to produce the plates ready to go on the press at a rapid rate; to strip the plate from the core by
- 25 the co-operation of the means for eliminating the riser; and to provide for completing the plates without producing chips or sawdust which sometimes cause trouble in the mechanism.
- 30 Additional objects and advantages of the invention will appear hereinafter.

Reference is to be had to the accompanying drawings in which

Fig. 1 is a cross section of one form of casting mold and metal pump and pot with a preferred embodiment of this invention applied thereto;

Fig. 2 is a plan of the same;

Fig. 3 is a sectional view on enlarged scale of the portion of the mold at which the

metal enters, showing an intermediate step of the operation of separating the still molten riser from the plate;

Fig. 4 is a sectional view of the mold and plate showing one plate ejected from the mold and ready to be removed and another plate just starting to be cast, the parts of the riser separating means being in a different position from those shown in Figs. 1 and 3;

Fig. 5 is a similar view showing the position of the parts when the whole operation is completed and the second plate is fully cast and its riser entirely separated; and

Fig. 6 is an enlarged sectional view similar to Fig. 3 showing a modification.

The conventional method of casting plates for rotary printing presses is to pour molten metal into a mold, in which a matrix has been placed. This mold is generally closed on all sides and edges except the edge through which the metal is poured. On this edge a "riser" is formed, which serves the purpose of a feeder, from which the shrinkage within the plate during the cooling process is supplied. This riser is generally so proportioned that it remains in a molten state while the plate is solidifying, so that a reservoir of molten metal is being maintained during that process.

From this it will be seen that it eventually becomes necessary to rid the cast plate of this riser, so that the plate may be produced with a straight finished edge instead of the irregularly shaped mass, found thereon by the riser. This makes it necessary to provide a device for severing the riser from the plate proper, usually in the shape of a cutting mechanism of one form or another, according to the idea of the designer and the demands of the machine. The process of cutting off the riser after it has solidified produces a quantity of chips or sawdust which are apt to clog the working parts of the machine and interfere with its operation. It also serves to slow down the production of plates, since a certain number of seconds is required for the act of cutting off the riser.

It has been suggested that the riser while

it still is in the molten state, can be cut off by means of a rotating valve or the like. This method has proved defective, however, because among other objections, no way has been found of cutting off the molten riser of a printing plate close enough to the edge of the type matter to avoid reducing the number of lines.

This has been because the valve devices proposed have never been able to sever the molten riser at a point nearer to the type than the edge of the matrix, which is used to secure the matrix in the mold. Thus, a blank space has had to be left on the plate edge equal in width to the clamping edge of the matrix which shortens the type surface of the plate by as many lines of type at least as the clamping edge of the matrix is wide.

As the shortening of the printing surface of a newspaper plate, in the direction of its curvature, reduces the number of type lines the page may carry, and as advertising is sold by the line, it has been necessary to bring the type area of a page to the uttermost edge of the printing plate. It is this limitation that has largely made impracticable the otherwise desirable method of cutting off the riser while in its molten state.

The invention is capable of use with an ordinary melting pot 1 located in a furnace casing 2 provided with a grate 3 or gas burners 4 under the pot as may be desired. The molten metal, as is well understood, is maintained at a level indicated by 5 in the melting pot. In this case it is pumped into a hopper 6 from which it is delivered into the mold. For the purpose of raising the metal from the pot 1 into the hopper 6 I have shown a pump 7 of the gear type driven by a shaft 8 from a sprocket 9 and chain 10 connected with a motor not shown. Of course any type of pump may be employed as that is not a feature of this invention.

The metal enters the pump 7 at a point 11 from the interior of the pot 1. It is forced up through a pipe 12 into the hopper 6 in which a level is maintained by an adjustable gate 13 past which any overflow may return to the pot 1 through an overflow tube 14 extending below the level 5. I have also shown a means for emptying the hopper comprising a valve 15, rod 16 and lever 17 for opening a port below and allowing the metal to flow back into the pot preferably under the level 5. An ordinary mixer 18 on the shaft 8 is indicated for the usual purpose.

The hopper 6 is provided with a spout 19 through which the metal is allowed to flow directly into the mold. The inside of the hopper 6 and the spout 19 are shown as provided with electrical heating elements 20

so that the temperature of the metal within may be maintained at any desired degree. Feeding wires 21 are shown for conducting a current to them, but if desired any other means may be employed. This constitutes the metal delivering means.

The mold comprises a casting box 22 which in this case is shown as forming the concave wall for receiving the matrix M and intended to be lowered to open the mold. This box is shown as having a horizontal axis and as provided with matrix bars 23 and clips 24 on its two upper edges. These hold the clamping edges of the matrix M and are arranged to strip the matrix from the cast plate when the casting box is lowered from the pouring position in the usual manner by an arm 44.

I have shown a core or cylinder 25 arranged to rotate about its own axis, and the axis of the casting box when in casting position, and forming the other side of the mold. I have not shown any specific means for rotating this core or for raising or lowering the box 22 as any means well known in this art can be employed.

The mold is so located with respect to the end of the spout 19, which is provided with a cylindrical end 19^a concentric with the curvature of the mold, that the metal will be delivered from the hopper 6 through this spout by gravity directly into the mold cavity between the core 25 and box 22 at one edge and preferably all along that edge. The matrix is clamped at each straight edge as shown in Fig. 3 between the edge of the bar 23 and clip 24 which covers the upper and inner edge of the matrix. Above it is the spout 19 which registers with it.

The mold is provided with an oscillating shutter or valve 29 adapted to swing on the surface of the core 25 about the center of that core. It extends throughout the length of the spout or nozzle 19. This shutter is operated by a link 30, lever 31, link 32 and cam 33 from the driving shaft 34 on which the cam is mounted. The latter link is shown as having a roll co-operating with the cam for that purpose. The cam 33 is shaped and timed to move the shutter 29 in a manner which will be pointed out later.

I find it advisable to prevent the chilling effect of the usual cooling water within the cylinder 25 from reaching that portion of the metal contained within the channel between the plate P and the interior of the nozzle 19. One means for accomplishing this is the provision of the cylinder or core 25 with an insulating area in the form of a cored hole 36, which when filled with air will not conduct the heat as rapidly as would a solid wall. Another way to do it is shown in Fig. 3, in which a much thicker solid wall is employed so that it will take longer for the heat to be dispersed through it. At any

rate some means is employed for insulating this part of the mold from the cooling devices which I have not illustrated herein, but which are ordinarily employed in this kind 5 of mold.

Of course the printing plate P is provided on its inner face with finishing strips p which are cast in suitable grooves 39 in the core for that purpose. On account of the 10 proximity of the adjacent group of grooves around the cylinder I find it advisable to provide a lip 40 at the lower edge of the shutter 29 projecting downwardly to prevent metal from running upwardly into the 15 grooves of the upper half of the cylinder.

Fig. 4 shows the position of the parts when the metal is being poured. It will be seen that the metal is free to flow into the mold cavity from the hopper and entirely 20 fill it. At this time the shutter 29 is in its uppermost position so that the channel into the mold is unobstructed. Now when it is desired to sever the connection between the partly cooled metal within the mold and the 25 molten metal within the passage of the spout 19 the shutter 29 is brought downward by the action of the cam 33, timed as stated to perform this operation at the exact instant indicated by the existing conditions. The 30 shutter 29 swings down around the axis of the core from the position shown in Fig. 4 to that shown in Fig. 3, thus partly closing the channel for the passage of metal between the mold and spout. The plate P is 35 nearly solidified by this time, which action may be hastened by the usual cooling methods. The shutter starts to move before the solidifying action is entirely completed.

Under the old conditions the metal in the 40 riser was kept in a molten condition on account of the greater cross sectional area of the riser so that the shrinkage of the metal in the mold was compensated for by the necessary descent of the metal into the mold 45 from the riser. In the present case, however, this shrinkage is compensated for by the descent of the shutter 29 into the mold and the forcing of the metal ahead of it inwardly toward the center of the mold cavity 50 if the shrinkage is such as to permit it to do so. If not, the shutter continues to advance until the surplus metal is forced out along the side of it as indicated by the curved 55 arrow in Fig. 3 when such metal goes back into the hopper. The operation of the shutter, of course, is so timed as to synchronize with the rate of cooling of the metal being used at that time. It does not shut the mold 60 passage instantaneously, but there is some dwell so that the surplus metal can be forced out. The timing is such that when the plate P becomes completely solidified and there is 65 no further need of supplying it with molten metal for the purpose of replenishing the

shrinkage incident to cooling, the shutter at that instant comes to its final position shown in Figs. 1 and 5. At that time it shuts off all communication between the mold and hopper 6 and the molten metal supply between the mold and the interior of the spout is forced out of the way by the advancing inclined edge of the shutter from the position shown in Fig. 3 to that shown in Fig. 5. In this way the supply of metal is entirely separated from the plate without the production of any riser at all, although all the advantages of a riser have been maintained through the various states of the cooling and solidifying action. Because of the construction shown there is no limitation placed upon the point to which the shutter 29 may descend. All metal but that actually used in the formation of the printing plate is displaced and eliminated from the plate. The metal in the spout 19 is maintained in a molten state whenever that is necessary by the heating elements 20. The riser edge of the plate is cast against the surface of the parts 24 and 29 which are finished to the proper shape to form the desired shape of this edge to permit it to be clamped properly on the cylinder of the press.

Fig. 1 shows the mold closed by the action of a cam 35, on the shaft 34, on the bell crank 44, or lever connection. The shutter 29 closes all communication between the hopper 6 and the mold cavity and is ready to rise by the action of the cam 33. When the shutter rises to the position shown in Fig. 4 the metal will flow in as indicated in that figure. Now as the plate cools and the cam 33 rotates the latter will act to move the shutter 29 down from the position shown in Fig. 4 to that shown in Figs. 1, 3 and 5 just as the metal reaches the proper stage for that action as described above. When the shutter rises again the casting box 22 drops away from the cylinder and the matrix is stripped by the parts 23 and 24. Now the cylinder or core 25 turns through a half revolution in the usual way so that the newly cast plate is delivered on its upper half. When this occurs the preceding plate P' meets a projection on the shutter 29 and is thereby lifted during its turning action away from the surface of the core 25. The plate is turned positively with the core and kept against its surface throughout its turning action up to this point by a notch 43 in the core which of course is filled by a projection on the plate. By the time the parts get to this position the shutter 29 has opened as shown in Fig. 4 so that a new plate P may be cast while the preceding plate P' is being removed from the machine by hand or otherwise. When the plate is delivered it may or may not be shaved along its inner ribs before being clamped down on the cylinder of the press. As there

is no riser and that edge of the plate is cast true against the surfaces of the parts 29 and 24 the entire finishing operation may in some instances be dispensed with.

5 In this way it will be seen that the riser sawing mechanism can be entirely eliminated and even the shaving means in some cases; that although the riser is not present and does not have to be manipulated, sawed 10 off or delivered, yet none of the advantages of the riser are lost. Furthermore, notwithstanding that the metal supply is separated from the cast plate while the former is in a fluid condition the plate is of no greater 15 length than a similar plate from which the riser has been sawed while cold. Neither is any blank space necessary on the edge of the plate conforming to the width of the clamping edge of the matrix and thus the type 20 surface of the plate does not have to be shortened. Furthermore the connection of the plate with the metal supply or riser is done away with without producing chips or sawdust which might clog the working parts 25 of the machine and interfere with its operation. This invention is also carried out with a corresponding increase in rate of production.

I do not claim herein the method or product as they are claimed in my original application, Serial No. 721,272. Although I have illustrated and described only a single form 30 of the invention and shown it as applied to a well known type of casting box and melting pot I am aware of the fact that modifications can be made in the invention itself and that it can be used with other types of 35 casting boxes and melting pots without departing from the scope of the invention as expressed in the claims.

40 Therefore I do not wish to be limited in these respects, but what I do claim is:—

1. In a casting machine, the combination with a mold, means for supplying molten 45 metal thereto, and means for opening and closing the mold, of means connected with the opening and closing means for automatically cutting off the supply of metal to the mold and ejecting the metal from the sprue.

50 2. In a casting machine, the combination with a mold having a passage leading to the mold cavity through which passage the metal flows to fill the mold, and means for closing the mold, of means for forcing the metal 55 out of said passage when the mold cavity proper is filled and means for operating said last mentioned means.

60 3. In a casting machine, the combination with a mold having a passage leading to the mold cavity through which passage the metal flows to fill the mold, and means for closing the mold, of means for forcing the metal 65 out of said passage when the mold cavity proper is filled, and applying pressure to the metal in the mold cavity, whereby the edge

of the casting at the point of supply will be left with a smooth cast surface and means for operating said last mentioned means.

4. In a casting machine, the combination with a mold, of co-operating means for first 70 closing the mold, then introducing metal into the mold, ejecting the surplus metal from the mold at the point of introduction, and opening the mold.

5. In a machine for casting a stereotype 75 printing plate without a riser, the combination with the core and back, of a movable member between the core and back at the point at which the metal enters the mold, and means for moving said member into the 80 mold after it is filled to eject the metal lying between the mold proper and the source of supply.

6. In a device for casting a stereotype 85 printing plate, the combination with a mold having a matrix holding device, and means for supplying molten metal thereto, of a movable member, and means for introducing the movable member into the mold to a position between the matrix holding 90 device and the opposite side of the mold cavity to eject the metal at that point and cast a plate without a blank end located along said matrix holding device.

7. In a device for casting a stereotype 95 printing plate, the combination with a mold having a matrix holding device, and means for supplying molten metal thereto, of a gate, and means for moving the gate up to the edge of the character forming area 100 of the matrix to separate the cast plate from its riser close to the printing surface of the plate.

8. In a machine for casting a stereotype 105 printing plate, the combination of a mold and a gate located at the intake edge thereof, with a hopper for containing molten metal located above the mold with a conduit at its bottom leading directly to the mold, and means for moving the gate into the conduit to close the conduit and prevent metal 110 solidifying therein.

9. The combination with a mold for a stereotype printing plate having a space for the introduction of molten metal, of means 115 movable bodily in a direction for stopping the flow of metal, forcing extra metal into the mold to supply any deficiency due to shrinkage, and cutting off the supply of metal at a point to prevent the formation 120 of a riser.

10. The combination with a mold consisting of two parts having a space between them and means communicating with said space for introducing molten metal thereinto, of a shutter movable in a direction 125 traverse to the adjacent side surfaces of the two parts of the mold toward the body of the mold, and means for moving said 130

shutter inwardly after the mold has been filled and the metal therein partially solidified for the purpose described.

11. In a machine for casting stereotype printing plates, the combination with a mold comprising two parts having at one edge a space through which metal can be introduced to fill the space between them, of a shutter movable along the surface of one of said parts toward the mold cavity through said space whereby the metal can flow into the mold when the shutter is withdrawn and means for forcing the shutter in toward the mold while the metal therein is only partly solidified to expel the surplus metal and cut it off from the cast plate.

12. In an apparatus for casting stereotype printing plates, the combination with a concave back and a convex core co-operating therewith to provide a mold space between them for a plate, of a spout having a surface constituting a continuation of the inside surface of said back and located adjacent thereto, means for supplying metal to the interior of said mold through the spout, and a shutter located between said surface of the spout and the convex surface of the core movable inwardly toward the mold cavity to cut off the interior of the spout entirely from the mold cavity.

13. In a device for casting molten metal for a printing plate, the combination with a concave back and a convex core spaced apart to form a mold for a curved stereotype printing plate, of a spout fitting against said back and spaced from said core the same distance as the back, whereby metal is free to flow through said spout into one edge of the mold cavity to fill the same and form a cast plate, and a shutter in the space between the surfaces of the spout and core outside the mold to close that space at that point, said shutter being movable inwardly along the surface of the core in engagement with the core to shut off all communication between the spout and plate cavity, said shutter having a lip at its edge to prevent metal from running into the grooves of the upper half of said core.

14. In a device for casting molten metal for a printing plate, the combination with a concave back and a convex core spaced apart to form a mold for stereotype printing plate, a spout fitting against said back and spaced from said core, and a shutter in the space between the spout and core to close that space at that point, said shutter being movable inwardly along the surface of the core to shut off all communication between the spout and plate cavity and mold the plate without a riser, of a matrix clamp on the same edge of the back, a clip for holding the edge of the matrix and molding a part of the surface of the edge of the plate, said

shutter being constructed and arranged to fit against the edge of said clamp and mold the balance of the edge surface of the plate.

15. In a stereotype plate casting machine, the combination with a concave back and a cylindrical double core therein, of means for introducing the molten metal into the space between the back and core, means for shutting off the metal from the mold cavity and supplying surplus metal to prevent the formation of a riser, said core having on each of its halves a notch so as to form a projection on the plate inside and cause the plate to be turned around with the core positively when the core is rotated. 80

16. In a stereotype plate casting machine, the combination with a concave back and a rotatable cylindrical double core therein, of means for introducing the molten metal into the space between the back and core, means for shutting off the metal from the mold cavity and supplying surplus metal to prevent the formation of a riser, said core having on each of its halves a notch so as to form a projection on the plate inside and cause the plate to be turned around with the core positively when the core is rotated, said shutter having means thereon for engaging the advance edge of the plate when ejected from the mold by the rotation of the core 90 and separating it from the core ready to be detached. 95

17. In a device for casting molten metal for a printing plate, the combination with a back and core spaced apart to form a mold 100 for a stereotype printing plate, a spout fitting against said back and spaced from said core, and a shutter in the space between the surfaces of the spout and the core to close that space at that point, said shutter being movable inwardly to shut off all communication between the spout and plate cavity and mold the plate without a riser, of means for cooling the interior of the core and means for retarding the conveying of heat from the 110 parts of the mold cavity adjacent to the entrance point for the molten metal in order to keep that part of the casting at a molten temperature after the rest of the casting is solidified. 115

18. In a device for casting molten metal for a printing plate, the combination with a back and core spaced apart to form a mold for a stereotype printing plate, of means for cooling the interior of the core and means for retarding the conveying of heat from the parts of the mold cavity adjacent to the entrance point for the molten metal in order to keep that part of the casting at a molten temperature after the rest of the casting is solidified. 120

19. In a mold for casting printing plates for rotary printing presses, the combination with the ingate funnel in said mold, of a 130

reciprocable pressure plate movable in a path in said mold adjacent to said funnel.

20. A mold of the character described having an ingate funnel and an adjacent guide passage therein, and a pressure plate reciprocable in said guide passage.

In testimony whereof I have hereunto affixed my signature.

HENRY A. WISE WOOD.
